UNITED STATES PATENT OFFICE.

OSCAR J. HOLMES, OF ST. LOUIS, MISSOURI.

GAS-EXHAUSTER FOR OIL-TANKS.

1,136,230.

Specification of Letters Patent. Patented Apr. 20, 1915.

Application filed November 10, 1913. Serial No. 800,174.

To all whom it may concern:

Be it known that I, OSCAR J. HOLMES, a citizen of the United States, and resident of St. Louis, Missouri, have invented certain new and useful Improvements in Gas-Exhausters for Oil-Tanks, of which the following is a specification containing a full, clear, and exact description, reference being had to the accompanying drawings, forming a part hereof.

My invention relates to improvements in gas exhausting apparatus for oil tanks, and the object of my invention is to construct a means for exhausting gas from oil tanks comprising a tubular gas conveyer, and a float for the support of the intake end of said conveyer whereby the float will automatically maintain the intake end of said conveyer at a point slightly above the oil surface in the region of the most dense gas.

In a companion application filed November 10, 1913, Serial No. 800,173 I illustrate, describe and claim a similar apparatus whereby the intake end of the gas exhausting means is positioned and held in place by a manually operated means.

With the above purposes in view my invention consists in certain novel features of construction and arrangement of parts as will be hereinafter more fully described, pointed out in the claims and illustrated by the accompanying drawings, in which—

Figure 1 shows in plan an oil tank with portions of the roof removed to show my improved gas exhausting apparatus and its relation to the internal braces of the tank; Fig. 2 is an enlarged, fragmental elevation of a tank with a portion removed to show the flexible gas exhausting pipe carried by a float; Fig. 3 is an enlarged, detail, sectional elevation of a pipe joint employed in my invention; Fig. 4 is a sectional plan illustrating in detail the means for guiding certain of the floating elements of my invention; Fig. 5 is an enlarged, detail elevation of the float guiding means; and Fig. 6 is a detail fragmental elevation illustrating relatively articulating float sections to provide for the passing of the internal tank braces.

Referring by numerals to the accompanying drawings: 7 designates an oil tank of the type commonly used for the storage of

crude oil and the like, which tanks are of great size and require internal braces such as 8 in order to stiffen the inclosing walls of the tank.

9 designates floats preferably formed hollow and of sheet metal. In outline each of the floats is shaped to conform with the braces 8 within the oil tank, as clearly shown in Figs. 1 and 4. Between each pair of floats is an articulating float section 10. Carried by the supporting float is a stub 11 and carried by the articulating float section is a pair of hinge bars 12, as clearly shown in Fig. 6. Arranged adjacent each corner of each float is a bracket 13 carrying a roller 14, and as a companion of the bracket 13 and roller 14 there is a bracket 15 carrying a roller 16, the bracket 15 being extended some considerable distance beyond the roller 16 so as to hold the float 9 elevated above the bottom of the tank in order to provide a working space for repairs and the like when the tank is empty. Secured to the braces 8 within the tank are the vertical guides 17 upon which the rollers 14 and 16 travel as the float rises and lowers with the body of oil. Carried by certain of the floats 9 are the pipe coupling-members 18 which extend through the floats and are open at their tops.

19 designates a pipe preferably located beneath and outside the tank 7 and has connected therewith a suction creating means 20. Secured in the bottom of the tank preferably vertically aligning with the pipe coupling 18 is a pipe coupling 21 in communication with the pipe 19, and connecting the pipe couplings 18 and 21 is a tubular conveyer 22 which is flexible and may be constructed either of material which is flexible itself or of a number of pipe sections having the hinged joints 22a. By this arrangement means is provided for exhausting the dense gas lying on the surface of the oil, the floats providing means for automatically maintaining the intake point of the exhausting means adjacent the surface of the oil at all times, regardless of its level, and the hinged sections of the floats providing a means whereby the floats may pass the braces within the tank. In addition to the floats providing a means for carrying the intake point of the exhausting apparatus at or about the surface of the oil, the floats

2
constitute a blanket or cover for the entire surface of oil, thereby minimizing evaporation and the production of gas.

I claim:

- 5 1. In combination with an oil tank having internal braces and vertical guides secured to said braces, a floating body within the tank between said guides, and floating bodies hingedly secured to the first mentioned body to articulate relative thereto, in order to provide for the movement of the floating body above and below said braces.
- 10 2. In combination with an oil tank having internal braces and vertical guides se-

cured to said braces, a plurality of floats arranged between said guides, certain of said floats having auxiliary, hinged float-sections to form articulating margins for the floats, a gas exhausting means, and a 20 flexible connection between said exhausting means and certain of said floats, substantially as shown and for the purposes stated.

In testimony whereof I have signed my name to this specification in presence of two 25 subscribing witnesses.

OSCAR J. HOLMES.
